UNITED STATES PATENT OFFICE.

CHARLES W. WHITE, OF NEW YORK, N. Y.

IMPROVEMENT IN ELECTRO-MAGNETIC STATION-INDICATORS.

Specification forming part of Letters Patent No. 154,309, dated August 18, 1874; application filed February 28, 1874.

To all whom it may concern:

Be it known that I, CHARLES W. WHITE, of New York city, in the county and State of New York, have invented a new and Improved Electro-Magnetic Station-Indicator, of which the following is a specification:

In the accompanying drawing, Figure 1 represents a vertical transverse section of my improved electro-magnetic station-indicator; Fig. 2, an end view of the same; and Fig. 3, a diagram, showing connection of indicator with battery in baggage-car.

Similar letters of reference indicate corresponding parts.

A represents an indicator; B, the ribbon, winding and unwinding on and from rolls C C journaled in case D. C¹ C¹ are gear-wheels on the shafts of these rolls, and connected by spur-wheel C², while E is a spur-wheel, and E² E² ratchet-wheels on shaft E¹, whose direction in rotating depends upon which of the ratchet-wheel turns it. The ratchets are turned by spring-pawls F F pivoted by links A² to the upper end of levers G that are attached to the armatures H' H' of magnets H H, and thrown up by spring L. These two sets of ratchet-wheels, pawls, levers, armatures, and magnets are disposed oppositely to each other—*i. e.*, so that one set shall turn the indicator in one direction and the other set will cause it to revolve in the opposite direction. The indicators are placed in any convenient position in the cars, and from each set

of magnets an independent circuit is led to the car, from whence the indicator is to be controlled, where a suitable circuit-making device is placed in each of the circuits. Upon one of these circuits being closed, the indicating-ribbon is caused to be unwound from the top roll and wound upon the lower roll, the other circuit being closed and the ribbon wound in the opposite direction.

So far I have described what is already known to the public.

I connect a spring check-pawl, M, working in a ratchet, M', on shaft E, with the pawls F by means of the levers N N, so that as a carrying-pawl, F, is operated, the check-pawl is lifted, and, as soon as the former returns to its place the latter locks in the ratchet M'. Thus I regulate the intermittent movements of the ribbon, the check-pawl and ratchet holding the rolls firmly and preventing its movement, so that the name on the indicating-ribbon is shown until the indicator be properly manipulated.

What I claim is—

The combination, with shaft E, ratchets E², and pawls F, of the ratchet M', check-pawl M, and levers N, arranged as and for the purpose specified.

CHAS. W. WHITE.
